RANGE INDEXING TELESCOPIC SIGHT MOUNT

Gerald J. Kraai, 1500 N. 78th Place, Apt. 6,
Kansas City, Kans. 66112

Filed June 20, 1974, Ser. No. 481,038

Term of patent 3½ years

Int. Cl. D22—99

U.S. Cl. D22—8

Fig. 1.

Fig. 3.

Fig. 2.

Fig. 4.

Fig. 5.

Fig. 6.

Fig. 7.

FIG. 1 is a perspective view of a range indexing telescopic sight mount showing my new design;

FIG. 2 is a side elevational view of the mount;

FIG. 3 is an end elevational view of the mount taken along line 3—3 of FIG. 2 in the direction of the arrows;

FIG. 4 is an end elevational view of the mount taken along line 4—4 of FIG. 2 in the direction of the arrows;

FIG. 5 is a top plan view of the mount;

FIG. 6 is a bottom plan view of the mount; and

FIG. 7 is a side elevational view of the mount, the side shown being the opposite side of that shown in FIG. 2.

I claim:

The ornamental design for a range indexing telescopic sight mount, as shown and described.
